CLAIM

The ornamental design for a castor oil pack, as shown and described.

DESCRIPTION

FIG. 1 is a top perspective view of a castor oil pack, showing my new design;
FIG. 2 is a perspective view of a castor oil pack in an alternate, unfolded state;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

(Continued)

The broken lines in the drawings illustrate portions of the castor oil pack which form no part of the claimed design.

1 Claim, 8 Drawing Sheets
